UNITED STATES PATENT OFFICE.

PATRICK J. SHANAHAN, OF NEW ORLEANS, LOUISIANA.

BRIDGE-WALL FOR BOILERS.

Application filed May 22, 1920. Serial No. 383,484.

To all whom it may concern:

Be it known that I, PATRICK J. SHANAHAN, a citizen of the United States, residing at New Orleans, in the parish of Orleans and State of Louisiana, have invented new and useful Improvements in Bridge Walls for Boilers, of which the following is a specification.

My present invention pertains to boilers, and it contemplates the provision in a boiler of means whereby a great saving of fuel is accomplished and this without affecting the heat radiating from the fuel in any degree.

The invention further contemplates the provision in a boiler of means whereby the flame from the heat is prevented from breaking and is carried upwardly and in a continuous manner and thus perfect combustion of the heat products is assured.

The invention will be fully understood from the following description and claim when the same are read in connection with the drawings, accompanying and forming part of this specification in which:

Figure 1, is a side elevation of a boiler and showing the fire confining walls in section.

Figure 2, is a section taken through the center drum and in the plane indicated by line 2—2 of Fig. 1.

Similar numerals of reference designate corresponding parts in both views of the drawings.

The boiler and its supports are of the construction shown or may be any other construction and are provided with the fire tubes 9; and at this point I would distinctly have it understood that the boiler and tubes constitute no part of my invention.

Arranged at the forward end of the boiler is the fire box 2 and forming the bottom of the box 2 are the grate bars 3.

Extending upwardly from the rear of grate bars 3 at an angle is a wall 4 and at its upper end this wall 4 merges into a bridge wall 5.

The bridge wall 5 comprises the essential feature of my invention and said wall is arranged approximately 5 inches from the bottom surface of the boiler. This wall 5 comprises a portion 6 and said portion is con-

structed so that it surrounds in semi-circular manner the under side of the boiler. By reference to Fig. 2 it will be seen that the portion 6 is slightly increased in thickness 55 toward the rear of the boiler and thus the space between the boiler and wall is slightly decreased away from the wall 5. At its inner end the portion 6 is secured to a rear wall 7 that has the arch 8. This construction will force the flame that travels over the bridge wall 5 to be confined closer to the boiler the further it passes to the rear of the device.

Because of the above mentioned construction, the flame will have a continuous upward passage and hence said flame is unbroken in its upward passage assuring perfect combustion at all times. This will manifestly cause more heat to be derived from 60 the fuel and said fuel will produce less smoke for passage to the tubes of the boiler.

It will be gathered from the foregoing that the invention is simple in construction and may be installed in any type of boiler 70 now in general use with but slight expenditure of money.

Having described my invention, what I claim and desire to secure by Letters-Patent is:

In means for the purpose set forth, the combination of a boiler, a fire box arranged beneath the forward end of the boiler, an inclined wall formed in rear of the fire box and sloping upwardly toward the boiler, an inclined wall pitched upwardly toward the rear of the boiler and abutting an arch wall in rear of the boiler, and a bridge wall formed at the forward end of the last named inclined wall and abutting against the upper end of the inclined wall that is arranged in rear of the fire box; said bridge wall terminating slightly below the boiler, and adapted to surround the sides and bottom of said boiler.

In testimony whereof I have hereunto set my hand in presence of two subscribing witnesses.

PATRICK J. SHANAHAN.
